UNITED STATES PATENT OFFICE.

NEAL T. MCKEE, OF BRONXVILLE, NEW YORK.

LOCOMOTIVE.

Application filed December 1, 1926. Serial No. 151,938.

My invention relates to locomotives and has particular reference to the operating mechanism for the locomotive throttle.

In modern locomotives the throttle is often located outside of the boiler in the steam line leading to the engine cylinders, and, in cases where a superheater is employed, between the superheater and the engine. As disclosed in Reissue Patent Number 16,285 granted to R. M. Brown, March 9th, 1926, the throttle is sometimes incorporated in the superheater header and in such cases the control rod for actuating the throttle is carried back to the engine cab outside of the boiler.

With the throttle located in the locomotive smoke-box, whether it is incorporated in the superheater or not, the use of an exterior control rod necessitates an additional packed joint in the smoke-box wall, which is difficult to keep tight, and therefore undesirable. Furthermore, the long rod necessary to reach from the smoke-box back to the cab involves a difference in expansion between the throttle rod and the boiler, and some form of compensating device must be employed to eliminate the effects of this differential expansion. The use of an exterior reach rod of this character is also undesirable not only because of its appearance, but also because it is desirable that the exterior of the boiler be kept as free as possible from additions to the already numerous auxiliaries mounted thereon.

The present invention is designed to eliminate the difficulties and disadvantages enumerated above by the provision of a throttle reach rod which passes through the interior of the boiler. The more detailed objects of the invention and the advantages to be derived from the use thereof will become apparent in connection with the following description of preferred examples of the invention which I have illustrated as applied to a locomotive equipped with a header throttle of the type disclosed in the previously mentioned patent.

In the accompanying drawings, Fig. 1 is a fragmentary longitudinal vertical section taken through a locomotive; Fig. 2 is a fragmentary transverse section, the right-hand half of which is taken on the line 2^a—2^a and the left-hand half of which is taken on the line 2^b—2^b; Fig. 3 an enlarged detail of construction; and Fig. 4 is a fragmentary view similar to Fig. 1 of a different form of the invention.

Referring now to Fig. 1, the main barrel of

the locomotive boiler is shown as formed by the sheet 10, with the fire-box formed by the crown sheet 11 joining the rear and forward sheets 12 and 13. The fire-box sheet 13 and the forward flue sheet 14 are joined by the usual smoke tubes 15 in which are located the superheater elements 16 connecting the superheater inlet header 17 with the outlet header 18 in which the throttle is located. The cam 60 shaft 19 operating the throttle terminates inside the line of the smoke-box wall (see Fig. 2), and has secured at its end a lever 20 to which is attached one end of the reach rod 21. In the ordinary type of locomotive the lower 65 end of the lever 20 will be above the line of the crown sheet 11, and the reach rod 21 is run back through the boiler inside a special tube 22 which is secured at one end in the flue sheet 14 and at the other end in the back head 70 75 80 85 90 95 100 105 110 sheet 13 of the boiler. The engineer's throttle lever 24 is preferably mounted directly on the sheet 23 forming the back head, and is connected to rod 21 in a manner to be described in detail later. The throttle lever 24 is provided with the usual ratchet lever 25 which operates in conjunction with any suitable mechanism for locking the lever in any desired position.

In order to prevent the leakage of air through the tube 22 into the smoke-box, a stuffing box must be provided around the rod 21 and because of the more moderate temperature at the rearward end of the tube, the stuffing box is preferably mounted on the rear head of the boiler. In this position the stuffing box is not only cooler but is also much more accessible.

The motion of rod 21 will not be one of pure translation because of the pivotal connection at its forward end, and the stuffing box must, therefore, allow for a small amount of vertical motion at the forward end of the rod. In order to accomplish this, I have shown a stuffing box comprising a plate 26 suitably secured to the boiler head and recessed to accommodate a suitable packing 27 which is held in place by means of the gland nut 28. As will be obvious from the figure, the passage through the plate 26 is tapered sufficiently to allow for the necessary vertical movement of the rod 21. In order to accommodate the pivotal motion of the lever 24, the rod 21 is preferably connected thereto by means of a pin 29 passing through a vertical slot 30 in lever 24. It will be obvious that the specific form of stuffing box employed and throttle lever connection used is immaterial,

as any form of construction which allows for the vertical movement of the rod 21 may be employed equally well, or by the use of suitable connecting links the motion of rod 21 may be made purely translational.

In Fig. 4 I have shown a mechanism for operating the throttle by means of rotary rather than longitudinal motion. In this construction the cam shaft 19 of the throttle is provided at its end with a segmental gear 20', the latter being actuated by a worm wheel 31 mounted on the forward end of the rod 21', the latter extending back to the boiler head through tube 22'.

The rod 21' is preferably hollow and of comparatively large diameter in order to prevent torsional distortion, and is supported at the rear end by a suitable plate and bearing 32 which forms a stuffing box preventing the passage of air through tube 22' into the smoke box. An operating hand-wheel 33 located in the cab serves the purpose of the conventional throttle lever.

It is particularly to be noted that when constructed in accordance with my invention the reach rod throughout its entire length is subjected to substantially the same temperature as that portion of the boiler and smoke-box through which it passes, and for this reason there will be substantially no differential expansion between the reach rod and the boiler. This makes possible the elimination of all compensating mechanism designed to take care of differential expansion and permits the use of a simple direct connection between the engineer's control means and the throttle.

While I have illustrated the invention in connection with a throttle located in the superheater header, it will be obvious that its application is not limited to this particular type of valve, and it will further be apparent that the invention may be applied to throttles located in the smoke-box arranged in such manner that the tube 22 must be located in a position in the boiler different from that shown. In some instances the superheater elements may be so distributed that there is insufficient room to locate the tube 22

as shown in the illustrative examples and in such cases the tube 22 and rod 21 may be located more centrally of the boiler and at a higher lever, with the necessary connection between the rod 21 and the throttle valve secured through any suitable form of linkage.

It will furthermore be apparent that elements other than the throttle operating means, such for example as the pipe carrying blower steam from the turret to the smoke-box, may be located in the tube 22.

The embodiments I have chosen are, therefore, not to be taken as limiting in sense, but as illustrative only, and the invention is to be limited only by the scope of the appended claims.

I claim:

1. In a locomotive, a boiler having a forward flue sheet, a back head and a crown sheet, a smoke-box located forward of said sheet, a throttle located in said smoke-box, a tube connected to said flue sheet and said head and passing through the boiler above the level of said crown sheet, a throttle operating rod passing through said tube, and packing means adjacent the back head between said tube and said rod.

2. In a locomotive, a boiler having a forward flue sheet and a back head, a smoke-box located forward of said sheet, a superheater having a header located in said smoke-box, a throttle in said header, a tube connected to said flue sheet and said head and passing through the boiler, a throttle operating rod passing through said tube, and packing means adjacent the back head between said tube and said rod.

3. In a locomotive, a boiler, a smoke-box forward of the boiler, a throttle located in said smoke-box, a throttle control member located at the rear of the boiler, and means located substantially entirely within the boiler and the smoke-box and exposed to the combustion gases for connecting said member with said throttle, whereby the temperature and consequent expansion of said means and of said boiler and smoke-box is substantially the same.

NEAL T. MCKEE.
